UNITED STATES PATENT OFFICE.

EMIL HENRIK WIDEGREN AND KLAS AUGUST WIDEGREN, OF ALBY, SWEDEN.

ELECTRIC WRITING-TELEGRAPH.

1,106,762.

Specification of Letters Patent. Patented Aug. 11, 1914.

Application filed December 20, 1913. Serial No. 807,919.

To all whom it may concern:

Be it known that we, EMIL HENRIK WIDEGREN and KLAS AUGUST WIDEGREN, subjects of the Kingdom of Sweden, and both residents of Alby, Sweden, have invented new and useful Improvements in Electric Writing-Telegraphs, of which the following is a specification.

The present invention relates to electric writing telegraphs in which, for transmitting the writing, there is used alternating current or pulsating current obtained from a source of continuous current effecting the movements of the recording pen of the receiving apparatus by means of suitable electromagnetic devices. In such apparatus it has been difficult to attain sufficient damping of the electromagnetic device of the receiver for preventing the latter from being influenced by the different variations or pulsations of the open current and having it to operate only on account of the virtual value of said current, as is necessary in systems of the present class for attaining an even writing free from vibrations. The present invention relates to improved means for obviating said inconvenience by a mechanical device rendering the recording pen practically independent of vibrations which may occur in the electromagnetic device effecting the movements of the said recording pen, so that an even writing identical with the writing put down in the transmitter is obtained in the receiver.

The invention is based on the observation that a spring fastened at the one end but for the rest freely movable, when being put into vibrations proceeding from the point of fastening, will obtain a node of vibration in a point at some distance from the free end of the spring. This observation is utilized in such manner that, for transmitting the movement from the vibrating electromagnetic device to the recording pen, a spring of the said kind is used, the movement being transmitted to the recording pen from the point of the spring in which the node of vibration is formed when the spring vibrates.

The invention is illustrated in the accompanying drawing in which—

Figure 1 displays the principle of the movement transmitting device used according to the invention, and Fig. 2, diagram-

matically, the application of the invention in a writing telegraph of the kind described in our U. S. A Patent No. 1054811.

Referring to Fig. 2, 1 and 2 designate two long-distance lines through which the electric pulsations transmitting the writing are conducted to the diaphragm relays 3 and 4 of the receiver, each of said relays breaking and closing a local circuit 5, 6 and 7, 8 respectively in accordance with the arriving pulsations. Said local circuits are shunted to other local circuits 9, 10 and 11, 12 respectively containing a continuous current source 13 and the oscillating coils 14 and 15 respectively of the electromagnetic devices of the receiver which devices are arranged according to the well known principle of the electrometer, the recording pen of the apparatus being acted upon by said electromagnetic devices with the aid of the arms 17 and 18 rigidly secured to the oscillating coils, and the rods 19 and 20. When the diaphragm relays 3 and 4 in rapid succession close and break their contacts 21 and 22 respectively, the oscillating coils become alternately short circuited and energized, so that through them passes a pulsating current having a number of pulsations corresponding to the number of pulsations of the current flowing through the long distance lines 1 and 2, resulting in that the oscillating coils easily obtain a vibrating movement which, if transmitted to the recording pen, would exert an unfavorable action on the distinctness of the writing. According to the present invention the said inconvenience is obviated by the rods 19 and 20 not being connected directly to the rigid arms 17 and 18, but to springs 23 and 24 attached to said arms, the connecting point of each spring being so located that it coincides, from practical point of view, with the node of vibration formed near to the free end of the spring on account of the vibrations of the oscillating coils. Fig. 1 shows how such a spring 23 vibrates in consequence of a vibration transmitted through the point of attachment.

25 designates the point in which the rod 19 is jointed to the spring.

26 is a weight placed at the end of the spring and being preferably movable along the spring thus permitting adjustability of the place in which the node of vibration of

the spring is formed so that said node may coincide as nearly as possible with the point 25, which may hardly be made adjustable.

It stands to reason that the invention is 5 not limited to the form shown on the drawing but may be applied to writing telegraphs of any kind in which not desirable vibrations may occur on account of the nature of the currents used for transmitting the 10 writing.

Having now described our invention, what we claim as new and desire to secure by Letters Patent is:

1. In electric writing telegraphs, the combination of a recording pen, oscillating electromagnetic devices, a spring attached to each of said electromagnetic devices, and means connecting the recording pen with said springs at a point thereof coinciding

with a node of vibration, substantially as 20 and for the purpose set forth.

2. In electric writing telegraphs, the combination of a recording pen, oscillating electromagnetic devices, a spring attached to each of said electromagnetic devices, means 25 connecting the recording pen with said springs at a point thereof coinciding with a node of vibration, and a weight attached adjustably to each spring, substantially as and for the purpose set forth.

In testimony that we claim the foregoing as our invention, we have signed our names in presence of two subscribing witnesses.

EMIL HENRIK WIDEGREN.

KLAS AUGUST WIDEGREN.
